UNITED STATES PATENT OFFICE

NELS G. JOHNSON, OF OAK PARK, ILLINOIS

PADLOCK

Application filed December 4, 1926. Serial No. 152,581.

This invention relates to padlocks and is fully described in the following specification and shown in the accompanying drawings, in which,

5 Figure 1 is a longitudinal section through a padlock embodying the invention, showing the same locked;

Fig. 2 is a transverse section on the line 2 of Fig. 1;

10 Fig. 3 is a view similar to Fig. 1 showing the same in unlocked position preparatory to removing the shackle;

Fig. 4 is a top plan view of the removable locking member;

15 Fig. 5 is a longitudinal section through the same on the line 5 of Fig. 4;

Fig. 6 is a detail of the key and locking member similar to that portion of Fig. 1, but showing the key completely inserted; 20 and

Fig. 7 is a detail view of the shackle partly in section taken on the line 7 of Fig. 3.

The embodiment illustrated comprises a lock having a body 10 in which are formed 25 two parallel openings 11 and 12, which are drilled nearly through the same and which are adapted to receive the two ends of the U-shaped shackle member 13. The shackle is made symmetrical so that either end of 30 the shackle may be placed in either of the openings 11 and 12.

The shackle is provided with oppositely arranged notches 14, and which are adapted to register with steel balls 15, the latter being loosely retained in pockets 16 so that they may be retracted as shown in Fig. 3 to permit the shackle 13 to be withdrawn.

The body 10 is provided with a central opening 17, into which is tightly driven or 40 otherwise securely held a plug 18 which is preferably stopped by an annular ledge 19. This plug is hollow and is threaded to receive a locking member 20. The locking member 20 also is drilled axially to receive 45 the rotatable member 21. A spring 22 bears at one end upon the rotatable member 21 and at the other upon a sleeve 23 which is rotatably mounted in the plug 18.

A key 24 is provided having a shank 25 and an extension 26, which is cut at a sharp

angle at its outer end as shown in Fig. 1 for a purpose which will now be explained. The extension 26 is illustrated as being square, but, if desired may be pentagonal, hexagonal, flat, rectangular and the like, in order to cause it to fit snugly into a similar shaped opening 27 in the locking member 20. For the key 24 to turn the locking member 20, it is necessary for the extension 26 to be forced into the opening 27.

From the foregoing it will be understood that, in order to prevent this lock from being picked, it is necessary that some provision be made to prevent any one without the proper key from getting into the opening 27. This I have accomplished by providing a steel ball 28 which ordinarily is held in front of the opening 27 by means of a spring 29. The purpose of the tapered end of the key 24 is now apparent. On inserting this key 70 this tapered end strikes the ball 28 and the key is revolved, the operator meanwhile pressing inwardly on the key until the tapered portion is turned so as to force the ball 28 to one side against the action of the spring 29. The key can then be forced past the ball so that the extension 26 substantially fills the opening 27.

With the key in place as shown in Fig. 6, the locking member 20 can be turned so as 80 to screw it into the plug 18, until eventually it will assume the position of Fig. 3. When in the position shown in Fig. 1, the locking member 20 lies squarely behind the steel balls 15 holding them in the notches 14 in 85 the shackle 13 so that the latter cannot be withdrawn from the body of the lock.

When the locking member 20 is screwed into the plug 18 as shown in Fig. 3, the steel balls 15 are free to move inwardly so as to 90 permit the shackle 13 to be withdrawn. With the shackle withdrawn the balls 15 are retained in the pockets 16 by means of collars 30 which have openings which are somewhat smaller than the balls.

The rotatable sleeve 23 is provided with one or more pins 31 which project inwardly and which engage corresponding slots 32 in the shank 25 of the key. By varying the number and size and arrangement of the 100

pins 31 and their corresponding slots 32 as well as the shapes of the extension 26 of the key and of its corresponding opening 27, a great number of keys may be provided 5 none of which will fit in any other lock than the one for which it is intended.

It will be noted that both the member 21 and the sleeve 23 are made freely rotatable so that when an instrument of any kind is 10 inserted the instrument bears not upon the locking member 20 but upon the rotatable member 21, or possibly upon the ball 28 which also is rotatable. Thus it will be seen that the locking member 20 cannot be 15 reached from the outside of the lock to be turned except by a key or the like which is able to move the ball 28 to one side so as to permit the key to be inserted into the splined opening 27.

20 To further insure against the locking member 20 being moved except by the proper key, I have provided in the face of the member 20 a depression 33 which is adapted to encounter a plug 34 which is pressed by 25 a spring 35 when the locking member 20 is screwed into the full locking depth as shown in Fig. 1.

All of the exposed portions of this lock 30 are treated as by pack hardening and the like so as to render them file proof. The result is a lock, which, while inexpensive to manufacture, is very effective and particularly 35 burglar proof.

While I have shown and described but a 35 single embodiment of the invention, it is to be understood that it is capable of many modifications. Changes, therefore, in the construction and arrangement may be made 40 which do not depart from the spirit and scope of the invention as disclosed in the appending claims.

What I claim is new and desire to secure by Letters Patent, is:

1. A lock comprising a U-shaped shackle, 45 a body having parallel openings adapted to receive the ends of said shackle, a notch in one of the ends of said shackle, a ball adapted to engage said notch, movable means for securing said ball in engagement 50 with said notch, and a rotatable member in said movable means to prevent a tool other than the key from being inserted into said means to turn the same.

2. A lock comprising a U-shaped shackle, 55 a body having parallel openings adapted to receive the ends of said shackle, a notch in one of the ends of said shackle, a ball, a rotatable sleeve in the body through which the key passes, said sleeve and key having 60 complementary mating portions, and a rotatable member in said rotatable sleeve to prevent a tool other than the key from being inserted into said means to turn the same.

3. A lock comprising a U-shaped shackle, 65 a body having parallel openings adapted to

receive the ends of said shackle, a notch in each of the ends of said shackle, balls held in the body and adapted to engage the notches when the shackle is inserted into said openings, movable means for locking 70 said balls in engagement with said notches, and a rotatable member in said movable means to prevent a tool other than the key from being inserted into said means to turn the same.

4. A lock comprising a U-shaped shackle, a body having parallel openings adapted to receive the ends of said shackle, a notch in each of the ends of said shackle, balls held in the body and adapted to engage the 80 notches when the shackle is inserted into said openings, a rotatable sleeve in the body through which the key passes, said sleeve and key having complementary mating portions, and a rotatable member in said movable sleeve, to prevent a tool other than the key from being inserted into said means to turn the same.

5. A lock comprising a U-shaped shackle, a body having parallel openings adapted to receive the ends of said shackle, a notch in one of the ends of said shackle, a ball, a member rotatable to lock said ball in said notch, said member having a central opening 90 adapted to receive a key, a movable element 95 adapted to prevent a tool other than the key from being inserted into said member to turn the same, said key and central opening beyond said ball having complementary engaging surfaces.

6. A lock comprising a U-shaped shackle, a body having parallel openings adapted to receive the ends of said shackle, a notch in one of the ends of said shackle, a ball, a member movable endwise to lock said ball in said notch, said member having a central opening adapted to receive a key having an inclined end, a movable element guarding 105 said opening against tools other than said key, and said key and central opening beyond said ball having complementary engaging surfaces.

7. A lock comprising a U-shaped shackle, a body having parallel openings adapted to receive the ends of said shackle, a notch in one of the ends of said shackle, a ball, a member screw threaded into a fixed part of the body and having a portion adapted to lock said ball in said notch, said member having a central opening adapted to receive a key, and a movable element guarding 115 said opening, said key and central opening beyond said ball having complementary engaging surfaces.

8. A lock comprising a U-shaped shackle, a body having parallel openings adapted to receive the ends of said shackle, a notch in one of the ends of said shackle, a ball, a member rotatable to lock said ball in said notch, said member having a central opening 125

adapted to receive a key with an inclined end, a spring-pressed ball guarding said opening against tools other than said key, said key and central opening beyond said ball having complementary engaging surfaces.

In testimony whereof, I have hereunto set my hand this 20th day of November, A. D. 1926.
